PACKAGE

Mildred Nell, New York, N. Y., assignor to Lucien Lelong, Inc., Chicago, Ill., a corporation of Illinois

Application June 10, 1937, Serial No. 147,502

6 Claims. (Cl. 206—1)

This invention relates to a multi-part container composed of wearable exterior parts and a refill box or package mounted in said parts and sealed thereby.

5 More specifically this invention relates to a powder container adapted to receive inexpensive cardboard powder boxes as refills therein.

In the dispensing of cosmetics such as face powders, and the like, great emphasis is placed 10 upon an attractive package or container for the product.

Heretofore when the contents of the package or container have been used, the package or container was thrown away. Since the price of the 15 package or container is a considerable item in determining the retail cost of the product, it is desirable to provide a cheap container thereby making possible a lower retail price for the product.

20 According to this invention, a container having an attractive appearance is provided and the cosmetics or other articles to be mounted in this container are packed in a separate cheap refill package or box that can be disposed of when its 25 contents are used up, while the exterior portions of the container are used over and over again. Thus it is necessary for the purchaser to obtain only one set of the exterior container members and to merely purchase the cheaper refill boxes 30 filled with cosmetics or other merchandise.

According to this invention the exterior members of the container are made of rigid materials, preferably molded plastics, while the refill package or box is made of cardboard or other cheap 35 material.

It is then an object of this invention to provide an attractive container for housing an inexpensive box or package.

A further object of this invention is to provide 40 molded plastic members forming an exterior container for a cardboard box.

A further object of this invention is to provide a multi-part powder box adapted to receive refill packages therein.

45 A further object of this invention is to provide a base member and a cover member composed of rigid plastic material and adapted to receive and seal therebetween an inexpensive cardboard box.

50 Other and further objects of this invention will become apparent to those skilled in the art from the following detailed description of the annexed sheet of drawings which discloses a preferred embodiment of the invention.

55 On the drawing:

Figure 1 is a side elevational view of the cover of a container according to this invention.

Figure 2 is a side elevational view of the refill package or box forming part of the container of this invention.

Figure 3 is a side elevational view of the base member of the container of this invention.

Figure 4 is an enlarged vertical cross-sectional view taken through a container or package according to this invention showing the parts 10 thereof in assembled relation.

Figure 5 is a vertical cross-sectional view taken through a combination tray member and sealing ring.

Figure 6 is a side elevational view of a powder 15 puff adapted to be carried by the tray member shown in Figure 5.

As shown on the drawing:

In Figures 1 and 4 the reference numeral 10 designates generally the cover member of a container according to this invention. The member 10 comprises a convex top portion 11, a cylindrical side wall 12 and a flat rim portion 13 between the convex top 11 and side wall 12. The cover 10 is preferably formed of a molded plastic. 20

The inner face of the cylindrical side wall is threaded near the bottom thereof as at 14.

As best shown in Figures 3 and 4, the reference numeral 15 designates generally the base of a container according to this invention. The 30 base 15 comprises a disc 16 having an upstanding annular flange 17 spaced from the outer periphery thereof. The flange 17 has a screw thread 18 on the outer face thereof.

As best shown in Figures 2 and 4, the reference 35 numeral 20 designates generally a cardboard box or refill package for housing the face powder or other material.

The box 20 can be formed by a simple stamping operation from a disc of cardboard and comprises a bottom wall 21 and a cylindrical side wall 22. The box 20 is open at the top thereof. 40

As shown in Figure 4, a resilient packing ring 23 may be disposed between the open top edge 45 of the box and the flat portion 13 of the cover for sealing the contents of the box against spilling. If desired the packing ring or washer 23 can be secured to the flat portion 13 of the cover 10. It is thus evident that a screwing down of the cover 10 on the base 15 compresses the washer 23 against the top edge of the box 20 and also secures the box between the base and cover. 50

The ring or washer 23 can be composed of any compressible material, such as felt, for example.

As shown in Figure 5, the packing ring 23 can 55

be replaced with a tray member designated generally by the reference numeral 25. The tray member 25 comprises a flat disc 26 adapted to fit on the box 20. The upper face of the disc 26 has secured thereon an annular ring or washer 27 to serve the same purpose as the washer or ring 23.

As shown in Figure 6, a powder puff 28 can be supported on the tray 25. When the tray 25 is mounted on the box 20 it will close the top of the box and when the powder puff 28 is disposed on the tray it can fit in the space 29 provided by the convex top portion 11 of the cover as shown in Figure 4.

From the above descriptions it should be understood that this invention provides a permanent exterior container or package for housing refill packages or boxes and that such refill packages or boxes are sealed in the exterior portions 20 of the container so that the contents thereof cannot be spilled from the container.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

30 1. A container comprising a molded plastic disc having an upstanding annular flange spaced from the outer periphery thereof, a screw thread on the exterior face of said flange, a cardboard box having a flat bottom wall seated on said disc and a cylindrical side wall abutting the inner face of said flange, a molded plastic cover member disposed over said box and having an internally threaded side wall for threaded engagement with the thread on said flange and a compressible 40 packing ring disposed between the top edge of the box and the cover whereby a screwing down of the cover on the base will compress the packing ring to seal the contents of the box in the container.

2. A powder box comprising a rigid base member having an upstanding annular flange spaced from the outer periphery thereof, a screw thread on the exterior face of said flange, a cardboard box seated on said disc having a cylindrical side wall abutting the inner face of the flange of the disc, a rigid cover member having a convex top portion, a cylindrical side wall portion and a flat rim portion between the convex portion and side wall portion, and a compressible sealing disc disposed between the top of the box and the flat rim 55 portion of the cover, said inner face of said side

wall being threaded near the bottom thereof for threaded engagement with the thread on the flange of the base whereby a screwing down of the cover on the base will compress the washer to seal the contents of the box and to hold the box 5 between the cover and base.

3. A powder box comprising a molded plastic disc having an upstanding annular flange spaced from the outer periphery thereof, an open topped cylindrical box seated on said disc in abutting 10 relation to the inner face of said flange, a tray member disposed on top of said box having a compressible periphery, a molded plastic cover having a convex top portion, a flat rim portion and a cylindrical side wall normal to the rim portion, 15 said side wall and said flange of the base having engaging screw threads thereon whereby a screwing down of the cover on the base will move the flat rim of the cover against the tray for compressing the periphery of the tray to seal the 20 contents of the box and to hold the box in assembled relation between the cover and base.

4. A package comprising a base member having a relatively short externally threaded upstanding annular flange, a container disposed on said base 25 in abutting relation to the inner face of the flange, said container having a side wall extending above said flange, a cover having a top portion thrusting against the top of the container and said cover having an internally threaded side wall 30 for threaded engagement with the flange on the base whereby a screwing down of the cover on the base will clamp the container between the cover and base.

5. A package comprising a base having an up- 35 standing annular flange, a container disposed on said base inside of the flange, said container having a portion extending above the flange, a cover having a top portion thrusting against the container and a side wall extending from said top 40 over the flange, and means detachably connecting said cover and said base to clamp the container between the cover and base.

6. A package comprising a base having an upstanding annular flange, a container disposed on 45 said base inside of the flange, said container having a portion extending above the flange, a cover having a top portion thrusting against the container and a side wall extending from said top over the flange, and mating engageable means on 50 said flange and said side wall drawing the cover and base together upon relative rotation thereof for clamping the container between the cover and base.
